CLAIM

The ornamental design for a grip for camera, as shown and described.

DESCRIPTION

FIG. 1 is a front perspective view of a grip for camera showing my new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof; and,

FIG. 8 is a left side view thereof.

The broken lines in the drawings are for purposes of illustration and form no part of the claimed design.
